(57) **CLAIM**

The ornamental design for a tasseled light string fixture, as shown and described.

DESCRIPTION

FIG. 1 is a perspective view of a tasseled light string fixture in accordance with a first embodiment;

FIG. 2 is a right side elevation view thereof, it being understood that a left side elevation view would be substantially identical thereto;

FIG. 3 is a front elevation view thereof, it being understood that a rear elevation view would be substantially identical thereto;

FIG. 4. is a top plan view thereof;

FIG. 5 is a bottom plan view thereof;

FIGS. 6-7 are respectively a perspective view and a right side elevation view of a tasseled light string fixture in accordance with a second embodiment, it being understood that left, front, and rear elevation views are substantially identical to the right side elevation view of FIG. 7 and that top and bottom plan views respectively correspond to the views shown in FIGS. 4-5; and,

FIGS. 8-9 are respectively a perspective view and a right side elevation view of a tasseled light string fixture in accordance with a third embodiment, it being understood that left, front, and rear elevation views are substantially identical to the right side elevation view of FIG. 9 and that top and bottom plan views respectively correspond to the views shown in FIGS. 4-5.

The cross hatching shading in the figures is fragmentarily shown for convenience of illustration, it being understood that the shading is uniformly continued over the surface in which it appears.
